UNITED STATES PATENT OFFICE.

ALBERT J. WEITH, OF CHICAGO, ILLINOIS.

OIL-PUMP.

SPECIFICATION forming part of Letters Patent No. 258,962, dated June 6, 1882.

Application filed March 11, 1882. (No model.)

To all whom it may concern:

Be it known that I, ALBERT J. WEITH, of Chicago, in the county of Cook and State of Illinois, have invented certain new and useful 5 Improvements in Oil-Pumps; and I do hereby declare that the following is a full, clear, and exact description thereof, reference being had to the accompanying drawings, and to the letters of reference marked thereon, which form 10 a part of this specification.

The nature of this invention relates to pumps for drawing oil from barrels or tanks; and it is my object to construct such a pump as will not permit an overflow or a leakage of oil 15 through the top of the plunger-rod opening, but will discharge such leakage through an opening below the air-chamber, to run back again into the barrel or tank, and to have other provisions, in connection with the air-chamber, 20 which will add to the perfect working of the pump, all as more fully hereinafter described and specifically claimed.

In the accompanying drawings, Figure 1 represents a vertical section through the center line of the pump; Fig. 2, an elevation of 25 same; Fig. 3, a section on horizontal line $x\ x$ in Fig. 1, and Fig. 4 a similar section on line $y\ y$ in Fig. 1.

Like letters designate corresponding parts 30 in all the figures.

A denotes a conical air-chamber, and B the pump-barrel, connected to the bottom of the same. This pump-barrel B is secured eccentrically to the air-chamber A in such a manner 35 that the plunger-rod C, that is passed through the center of such air-chamber, will pass down into such barrel at or near one side of the same. This plunger-rod has a handle, a, to its upper extremity, and a hook, b, to its bottom end, 40 which connects with the plunger D, having valve d.

The plunger-rod C is guided in a tube, e, that projects through the air-chamber A, and is hermetically secured to the top and bottom 45 plates of such air-chamber in such a manner that the interior opening in said tube is in no communication with the interior of the air-chamber.

Just below the tube e, underneath the air-chamber A, at p, a portion of the pump-barrel

B is cut out, so as to expose the plunger-rod C, and below such cut or notch p the pump-rod is guided again in a short tube, f, that is soldered to the barrel. An arch-shaped plate of metal, or a segmental section, g, of a pipe is placed behind the flues e and f, so as to form a connection of the same, and a partition between the interior of the pump-barrel B and the exposed portion of the pump-rod, thus forming a niche in said barrel, through which 55 such plunger-rod reciprocates; and the ends of the tubes e f are formed with air-tight connections at the junction of the pump-barrel B and plate g.

The interior of the air-chamber A communicates with the pump-barrel B through an opening at their jointing-point, and the discharge-pipe E is projected through the top of the air-chamber A, where it is secured by an air-tight joint, and is thence projected downward into 70 the pump-barrel B, so as to leave an open space around it. The top end of this discharge-pipe E is curved to spout the oil downward above and to one side of the air-chamber A.

The seat h for a valve, i, is secured in the bottom end of barrel B, and below this is fixed a bow-shaped support, j, on which the pump will rest in the bottom of the barrel.

The seat m for a check-valve, n, is inserted in the pump-barrel B behind plate g, and just below the end of discharge-pipe D.

This pump being inserted with its barrel into the bung-hole of a barrel containing oil, and so that bow j rests upon the bottom of such barrel, and the plunger-rod C being reciprocated, with each upward stroke oil will be drawn into the pump-barrel B through valve i, while an equal amount of oil that is above the plunger D will be forced upward through the discharge-pipe E, and with each 85 downstroke of the plunger the valve i will close and the oil in the pump-barrel underneath the plunger D will pass through valve d into the pump-barrel above the plunger D. The discharge-nozzle E, extending higher than 90 the top of tube e, with pumping, a certain amount of oil would be forced through the space around the plunger-rod if such tubes e and f were continuous, and unless the tube e was provided with a stuffing-box that would 95 100

close the joint around the plunger-rod hermetically. Such stuffing-box would, however, make the plunger-rod work hard, and would require frequent repacking, while without it the leakage through the top of tube *e* would cover the exterior surfaces of the air-chamber and the pump-handles with oil and grease, and would make the operation of drawing oil a nasty job, beside the waste connected therewith.

15 By my arrangement, as will be noticed, the escape of any such leakage will be through the top of the tube *f*, whence the oil will run from the niche down and back into the barrel, and the air-chamber and pump-handle will be kept clean.

The air-chamber around tube *e* being perfectly tight and only communicating with the pump-barrel, and the discharge-nozzle *E* extending into such pump-barrel a desired distance, the oil can never rise into such air-chamber unless the pump was being turned upside down while its barrel is filled with oil. The advantage of this arrangement is that the elasticity of the air in the chamber *A* is utilized to better advantage.

20 The check-valve *n* will be closed by the pressure of the oil that is above and in nozzle *E*, and will prevent such oil from escaping through the top of tube *f* while the pump is at rest or 30 while it is removed from the oil-barrel. This valve *n*, however, is not essential, and can be dispensed with by arranging the top of tube *f* with a stuffing-box for hermetically closing the joint around the plunger-rod *C*.

35 As will be noticed, this pump is simple in construction, and will insure a clean pumping operation.

What I claim is—

1. In an oil-pump having an air-chamber 40 above the pump-barrel and a discharge-nozzle extending above such air-chamber, an opening below such air-chamber that communicates with the inside of the tube or tubes for guiding the plunger-rod, and which furnishes an 45 outlet for any oil forced into or through such tube, all substantially in the manner set forth.

2. In oil-pumps, the air-chamber *A*, having central tube, *e*, for guiding the plunger-rod *C*, and discharge-nozzle *E*, in combination with

the pump-barrel *B*, eccentrically connected with such air-chamber *A*, substantially as and for the purpose set forth.

3. In oil-pumps, the air-chamber *A*, having central tube, *e*, for guiding the plunger-rod *C*, such tube *e* extending through both ends of the air-chamber, and being connected therein by air-tight joints, substantially as and for the purpose set forth.

4. In oil-pumps, the air-chamber *A*, having central tube, *e*, for guiding the plunger-rod *C*, and the pump-barrel *B*, eccentrically connected with such air-chamber *A*, in combination with the discharge-nozzle *E*, extending through the air-chamber into such pump-barrel *B*, all substantially as and for the purpose described and shown.

5. In oil-pumps, the air-chamber *A*, having tube *e*, and the pump-barrel *B*, having notch *p*, tube *f*, and partition *g*, in combination with the pump-rod passing through and guided in tubes *e* and *f*, all substantially as and for the purpose set forth.

6. In oil-pumps, the air-chamber *A*, having central tube, *e*, and the pump-barrel *B*, connected eccentrically with such air-chamber *A*, 75 and having notch *p*, tube *f*, and partition *g*, in combination with the plunger-rod *C*, passed through the tubes *e* and *f*, and with the discharge-nozzle *E*, projected through the air-chamber *A* and into the pump-barrel *B*, all substantially as and for the purpose set forth.

7. In oil-pumps, the air-chamber *A*, having central tube, *e*, and the pump-barrel *B*, connected eccentrically with such air-chamber *A*, and having notch *p*, tube *f*, partition *g*, and 85 check-valve *n*, in combination with plunger-rod *C*, passed through the tubes *e* and *f*, and with the discharge-nozzle *E*, projected through the air-chamber *A* and into the pump-barrel *B*, all substantially as and for the purpose set forth.

In testimony that I claim the foregoing as my invention I affix my signature in presence of two witnesses.

ALBERT. J. WEITH.
